DESIGN.

—o—
H. HUNT.

CARPET.

No. 18,157.

Patented Mar. 6, 1888.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 18,157, dated March 6, 1888.

Application filed January 26, 1888. Serial No. 262,087. Term of patent 3½ years.

To all whom it may concern:

Be it known that I, HENRY HUNT, of Greenville, New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design consists of a series of conventionalized leaf forms, over which are scattered in groups of two or more, or singly, round fruit

forms resembling chestnut-burrs. The leaf forms are similar in character, being divided by deep serrations into a number of parts or lobes. The burr forms are arranged in groups of varying size and number, overlying the leaf forms and generally connecting several of the leaf forms. Here and there a burr form occurs singly in the intervening spaces, or overlying or partly underlying a leaf form.

What I claim as new, and desire to secure by Letters Patent, is—

The design for carpets, consisting of the design substantially as shown.

HENRY HUNT.
